UNITED STATES PATENT OFFICE.

JOSEPH G. COFFIN, OF GARDEN CITY, NEW YORK, ASSIGNOR, BY MESNE ASSIGNMENTS, TO CURTISS AEROPLANE AND MOTOR CORPORATION, OF BUFFALO, NEW YORK, A CORPORATION OF NEW YORK.

METHOD OF AND APPARATUS FOR MAKING AEROFOILS AND THE LIKE.

1,386,841.

Specification of Letters Patent. Patented Aug. 9, 1921.

Application filed March 14, 1919. Serial No. 262,682.

To all whom it may concern:

Be it known that I, JOSEPH G. COFFIN, a citizen of the United States, residing at Garden City, in the county of Nassau and State of New York, have invented certain new and useful Improvements in Methods of and Apparatus for Making Aerofoils and the like, of which the following is a specification.

My invention relates to an improved method of and apparatus for making aerofoils and the like, and especially model aerofoils. Such aerofoils, which include wings, rudders, ailerons, elevators, etc. are used extensively in aeronautical research and experimental work. They are especially useful in conducting wind tunnel experiments to determine the properties and characteristics of various types and designs of aeroplane wings. The use, however, to which the model aerofoils can be put is unlimited. If sufficiently reinforced, as hereinafter explained, such aerofoils are admirably suited to aeroplane model construction.

Heretofore it has been the practice in making model aerofoils to use either wood or metal (or both) as a basis. The use of wood, in this connection, is objectionable. It is objectionable; first, because of the more or less expert labor required by the maker; second, because of the impossibility of obtaining absolute accuracy without the exercise of infinite care; third, because of the fact that a slight defect in the making renders the aerofoil in its entirety worthless; fourth, because of the time required in the making, and fifth, because of the production cost, which, in view of the skilled labor and the time required, is enormous. The use of metal as a basis is objectionable for similar reasons. In either or both instances special jigs, patterns, etc. are required. It is obvious, therefore, that the demand for a cheaper and better method of making model aerofoils is strong. Especially is this true when it is considered that quality and not quantity is required and that for each experiment a distinctly different character or design of aerofoil is used.

It is an object of the present invention, in view of the foregoing, to render the making of model aerofoils less tedious, less expensive, more rapid and (of greatest importance) more accurate. In its preferred embodiment the invention contemplates the use

of a plastic composition as a basis for the model aerofoils. The method of making the aerofoils consists in first providing a bed of a substance susceptible of being scraped (paraffin, for instance), next scraping the bed until one surface thereof approximates one surface of the finished aerofoil, next coating the scraped surface with a substance in turn susceptible of being scraped (plaster of Paris, for instance), next scraping the coating substance until the surface thereof remote from the bed approximates the other surface of the finished aerofoil, and finally removing the scraped coating substance from the bed in the form given it by the bed in conjunction with the scraping. Additional steps may be incorporated. As an example, it is preferred that the bed be lubricated or greased to prevent cohesion of the plastic composition with the paraffin. An alternative is the heating of the paraffin to a melting temperature after the plastic composition has set. Also, for added strength, it is preferred that a core or filler be embedded in the aerofoil during the making thereof. Furthermore, a coating (of veneer or varnish for instance) may be applied to the finished aerofoil to give it gloss and at the same time materially add to its strength.

The apparatus for making the aerofoils according to the method above outlined is also characterized by novelty. It comprises preferably a bed upon which the aerofoil is laid, scrapers, the scrapers being used in predetermined order or sequence and a carriage to which the scrapers are fastened, the carriage being adjustable toward and away from the bed to regulate the depth of the cut. In practice the carriage is moved back and forth across the bed, first with the scraper designed to scrape the bed, and secondly, with a scraper designed to scrape the aerofoil. Other characteristics of the invention will be hereinafter more particularly pointed out.

Of the drawings,

Figure 1 is a side elevation of the apparatus illustrating a preferred embodiment thereof.

Fig. 2 is a plan view.

Fig. 3 is an enlarged transverse sectional view showing the manner in which the scraper or templet used for cutting the par-

100

105

affin is formed, and also the manner in which the carriage is supported,

Fig. 4 is a similar view showing the manner in which the scraper or templet used for cutting the plastic composition of the aerofoil is formed,

Fig. 5 is a detail perspective view of the carriage,

Fig. 6 is a fragmentary sectional view showing the connection between the templet holder and the carriage,

Fig. 7 is a perspective view of the finished aerofoil showing the manner in which it is supported when used in the wind tunnel, 15 and,

Fig. 8 is a detail transverse sectional view of the aerofoil showing the character of connection used for supporting it in the wind tunnel.

20 The apparatus by which the method of making aerofoils and the like is carried into effect comprises a stand 10 having a length to width ratio corresponding with the length to width ratio of the average model aerofoil. At its opposite sides it is provided with rails 11 and 12 coextensive with the stand and parallel. The rail 11 has a convexed tread 13 which is substantially complementary with a groove 14 formed in an 25 enlargement 15 of the carriage. The rail 12, unlike the rail 11, is provided with a flat tread 16. The tread 16 in conjunction with a thumb screw 17 constitutes an adjusting means for the carriage.

30 The carriage, designated as an entirety by the numeral 18, in addition to the enlargement 15, is provided with a recess 19 for the holder 20. The carriage extends transversely across the frame 10 and is supported thereupon by the rails 11 and 12 which act as guides. A bed or container 21 of approximately the size of the frame 10 is supported thereupon between the rails 11 and 12 and between the end walls 22 and 23 35 of the frame. The bed plate rests directly upon the bottom of the frame which, for the sake of lightness, comprises a plurality of braces 24 which cross connect the side rails 11 and 12. To center the container within the frame to insure proper positioning thereof pins 25 are provided at the end 23 of the frame. These pins engage in recesses 26 formed in one end of the container and together with an adjustable pin 27 in 40 the form of a set screw constitute the centering means. The adjustable pin 27 is likewise adapted to engage in a recess 28 formed in the end 22 of the container. By first placing the container within the frame 45 in such manner that the pins 25 are seated in the recesses 26 and thereafter adjusting the pin 27 with respect to the recess 28 it is evident that the container will be properly centered with respect to its support. In the 50 operation of the apparatus for making aero-

foils of a given design two templets are used. These templets are made preferably together. In making the templets the ordinates of the aerofoil profile to be made are indicated on a flat pattern of a given size, 70 *i. e.* a size measured to fit a slot 29 formed in the holder 20. To this marked pattern a second pattern is glued or otherwise fastened. The two patterns are then cut as indicated by the ordinates or rather by the 75 markings indicating the under surface of the aerofoil as it is formed by the apparatus, which is in reality the top surface of the aerofoil as actually used. The two patterns are then separated and one of them 80 (the one marked) cut along the line indicating the opposite surface of the aerofoil. In this way two templets having similar characteristics, though different working edges, are provided. This manner of making the 85 templets also insures absolute accuracy since in making them together the ends exactly coincide. Either before or after making the first cut, and while the patterns are fastened together, (preferably) three holes 30 are 90 formed in the templets to register with a like number of holes 31 formed in the holder 20. Pins 32, which fit the registering holes in the templet and holder respectively provide the fastening means for the templet in 95 use.

In the use of the apparatus, the templets, designated respectively 33 and 34, are used in sequence. That is to say, the templet 33 is used first to scrape the contents of the 100 container and the templet 34 subsequently used to scrape the exposed surface of the aerofoil, *i. e.* that surface of the aerofoil remote from the bed upon which it is formed. Paraffin or the like is preferably used as the 105 bed because of its inherent qualities. It is preferred, not only because of its translucency but principally because of its susceptibility of being readily scraped.

The means for locking the holder in the 110 recess 19 of the carriage comprises thumb screws 35 and 36. The thumb screw 36 is provided at one end of the carriage and is adjustable toward and from the corresponding end of the holder to force it (the holder) 115 firmly against the opposite end wall of the recess. After adjusting the thumb screw 36 the thumb screws 35, of which there are two, are tightened and the holder thus held firmly against one of the side walls of the 120 recess. In this way the holder is rigidly held in place.

In the use of the apparatus the carriage 125 is reciprocated or moved back and forth longitudinally of the frame. It is guided in its movement by the rail 11 and is adjusted toward and from the paraffin bed by the thumb screw 17. The thumb screw 17 bears directly upon the top flat surface 130 of the rail 12 to regulate the depth of cut

made in the paraffin as the carriage is moved back and forth. This is desirable as by adjusting the thumb screw gradually a gradual cut can be effected and extreme accuracy 5 obtained in the formation of the groove in the bed. To enhance the accuracy the knurled end of the nut 17 is graduated as indicated at 37, the graduation marks when used in connection with a pointer 38 indicating the adjustment to a small fraction 10 of an inch.

After having filled the container with paraffin and after having made the templets as desired the templet 33 is fastened in place 15 until its working edge bears upon the paraffin. The carriage is then reciprocated and the thumb nut adjusted until the depth of cut desired is made in the paraffin bed. The templet 33 is then removed from the holder 20 and the templet 34 fastened in its stead. Before again reciprocating the carriage the plastic composition, preferably consisting of plaster Paris as a basis is poured over the bed to completely fill the groove formed 25 in the paraffin. If it is desired that the aerofoil be made amply strong a core or filler 39 is then embedded in the soft plastic composition. Having embedded the core or filler as stated a further amount of liquid plastic composition is applied to the 30 bed, the amount being sufficient to completely cover the core or filler. The carriage is then again reciprocated with the templet 34 in place. This reciprocation of 35 the carriage causes the templet to scrape the plastic composition and thus remove that which is superfluous. In operating the carriage for the second time the thumb nut 17 is again manipulated until satisfactory 40 results are obtained. Meanwhile and during the second reciprocation of the carriage the plastic composition is congealing or hardening. When thoroughly dried or set 45 the plastic composition with the core embedded therein is removed from the paraffin bed in the form given it by the bed in conjunction with the templet 34. If desired, the plastic composition which at this stage 50 of the operation is in reality the model aerofoil, may be given a coat of varnish or veneer for the purpose of strengthening it and for the additional purpose of giving the model aerofoil a gloss.

To avoid any difficulty which might be 55 encountered in removing the paraffin bed the paraffin may be heated to a melting temperature, and the aerofoil then easily removed. Or, if desired, a coating of lubricant or grease may be applied to the grooved 60 surface of the paraffin before the application of the plastic composition to prevent its cohesion with the paraffin bed.

Instead of using paraffin in the first stage 65 of the operation a plastic composition such as that used in the formation of the aero-

foil may be used although from practical experience paraffin has been found the better for reasons above pointed out. Also, if desired, the core or filler may be omitted and the coating of varnish or veneer applied after the removal of the aerofoil relied upon to give the aerofoil strength. The core or filler, however, is best in that adequate strength is assured for all practical purposes in making subsequent wind tunnel 75 tests.

A big advantage, other than the advantages above pointed out, in using the plastic composition as a basis for the model aerofoil is that all irregularities appearing upon the surface of the aerofoil during the making thereof may be wiped out by the application of an additional thin coating of the liquid plastic composition and a further reciprocation of the templet 34. This procedure insures a smooth finish and high accuracy in the making of the model. The only really accurate work involved is that exercised in the making of the templets for if the working edges of the templets are correct the finished aerofoil is bound to have a profile exactly according to design. Any number of model aerofoils may be made with the same templet, the operation in each instance being as outlined above. If 90 desired, an adjusting screw may be provided at each side of the frame to adjust either or both ends of the carriage although a single adjusting screw has been found to give perfectly satisfactory results. 100

Should the paraffin bed, for any reason be mutilated and the form given its working surface by the templet 33 become unsatisfactory, it is only necessary to melt the paraffin within the container, again scrape its working surface, and then continue the operation as before. Such advantages cannot help but add to the desirability of such an apparatus since the difficulties experienced in previous practice, where wood and metal have been used, are completely overcome. 110

Where the model aerofoil is to be used for making wind tunnel tests, the core or filler 39 is provided with a threaded opening 40 which is apparent even in the completed aerofoil due to the thinness of the plastic composition upon the opposite faces of the core. Being thus apparent the opening acts as a guide for drilling the hole through the aerofoil to admit of its ready use with the ordinary spindle 41 of a wind tunnel balance. In this connection reference should be had to Figs. 7 and 8 of the drawings. 120

In the foregoing the method of making the model aerofoils becomes apparent and since the method and apparatus are inseparable claims to both conclude the explanation and description of my invention. 125

While I have described my invention in 130

detail in its present embodiment, it will be obvious to those skilled in the art after understanding my invention, that various changes and modifications may be made 5 therein without departing from the spirit or scope thereof. I aim in the appended claims to cover all such modifications and changes. In this connection it may be noted that I consider cutting the bed and the aero- 10 foil the equivalent of scraping, although I have used the words "scrape" and "scraping" in drafting the claims.

What is claimed is:

1. The method of forming and producing 15 aerofoils or the like which consists in first providing a bed of paraffin or the like, next scraping the bed until one surface thereof approximates one surface of the finished aerofoil, next coating the scraped surface of 20 the bed with a substance in turn susceptible of being scraped, next scraping the coating substance until the surface thereof remote from the bed approximates the other surface of the finished aerofoil, and finally removing the scraped coating substance from the bed in the form given it by the bed in conjunction with the scraping.

2. The method of forming and producing 30 aerofoils or the like which consists in first providing a bed of paraffin or the like, next scraping the bed until one surface thereof approximates one surface of the finished aerofoil, next coating the scraped surface 35 of the bed with a plastic composition in turn susceptible of being scraped, next scraping the plastic composition until the surface thereof remote from the bed approximates the other surface of the finished aerofoil, and finally removing the plastic composition 40 from the bed in the form given it by the bed in conjunction with the scraping.

3. The method of forming and producing 45 aerofoils or the like which consists in first providing a bed of a substance susceptible of being scraped, next scraping the bed until one surface thereof approximates one surface of the finished aerofoil, next coating the scraped surface of the bed with a substance susceptible 50 of having embedded therein a filler or core, next embedding the filler or core in the coating substance, next coating the core or filler with a substance susceptible of being scraped, next scraping the coating last applied until the surface thereof remote 55 from the bed approximates the other surface of the finished aerofoil and finally removing the coating substance with the core or filler embedded therein from the bed in the form given it by the bed in conjunction with the scraping.

4. The method of forming and producing 60 aerofoils or the like which consists in first providing a bed of a substance susceptible of being scraped, next scraping the bed until one surface thereof approximates one surface

of the finished aerofoil, next coating the scraped surface of the bed with a plastic composition, next embedding a core or filler in the plastic composition, next coating the core or filler by the application of an additional 70 amount of plastic composition, next scraping the plastic composition until the surface thereof remote from the bed approximates the other surface of the finished aerofoil and finally removing the plastic composition 75 from the bed with the core or filler embedded therein in the form given it by the bed in conjunction with the scraping.

5. The method of forming and producing 80 aerofoils or the like which consists in first providing a bed or paraffin or the like, next scraping the bed until one surface thereof approximates one surface of the finished aerofoil, next coating the scraped surface of 85 the bed with a substance susceptible of having embedded therein a core or filler, next embedding the core or filler in the coating substance, next applying an additional amount of the coating substance sufficient to cover up the core or filler, the coating substance being in turn susceptible of being scraped, next scraping the coating substance until the surface thereof remote from the bed approximates the other surface of the finished aerofoil and finally removing the 90 scraped coating substance from the bed with the core or filler embedded therein in the form given it by the bed in conjunction with the scraping.

6. The method of forming and producing 100 aerofoils or the like which consists in first providing a bed of paraffin or the like, next scraping the bed until one surface thereof approximates one surface of the finished aerofoil, next coating the scraped surface of 105 the bed with a plastic composition susceptible of having embedded therein a core or filler, next embedding the core or filler in the plastic composition, next applying an additional amount of plastic composition 110 sufficient to cover the core or filler, next scraping the plastic composition until the surface thereof remote from the bed approximates the other surface of the finished aerofoil, and finally removing the plastic composition 115 from the bed with the core or filler embedded therein in the form given it by the bed in conjunction with the scraping.

7. The method of forming and producing 120 aerofoils or the like which consists in first providing a bed of substance susceptible of being scraped, next scraping the bed until one surface thereof approximates one surface of the finished aerofoil, next coating the scraped surface of the bed with a liquid substance in turn susceptible of being scraped, the character of the liquid substance being such that it will in time congeal and ultimately harden, next embedding in the liquid substance (before it hardens) a reinforcing 125 130

- element or core, next scraping the liquid substance (with the core embedded therein) as it begins to congeal and harden until the surface thereof remote from the bed approximates the other surface of the finished aerofoil, and finally removing the reinforced scraped substance from the bed after it has hardened in the form given it by the bed in conjunction with the scraping.
- 10 8. The method of forming and producing model aerofoils which consists in first providing a bed of paraffin or the like, next scraping the bed until one surface thereof approximates one surface of the finished aerofoil, next coating the scraped surface of the bed with a substance in turn susceptible of being scraped, next scraping the coating substance until the surface thereof remote from the bed approximates the other surface of the finished aerofoil, next heating the paraffin to prevent the adhesion of the coating substance with the bed and finally removing the scraped coating substance from the bed in the form given it by the bed in conjunction with the scraping.
- 15 9. The method of forming and producing model aerofoils which consists in first providing a bed of the substance susceptible of being scraped, next scraping the bed until one surface thereof approximates one surface of the finished aerofoil, next coating the scraped surface with a substance in turn susceptible of being scraped, next scraping the coating substance until the surface thereof remote from the bed approximates the other surface of the finished aerofoil, next removing the scraped coating surface from the bed in the form given it by the bed in conjunction with the coating, and finally coating the removed product with a strengthening compound such as varnish.
- 20 10. A method of forming and producing model aerofoils which consists in first providing a bed of a substance susceptible of being scraped, next scraping the bed until one surface thereof approximates one surface of the finished aerofoil, next coating the scraped surface of the bed with a suitable lubricant or grease, next coating the greased surface of the bed with a substance in turn susceptible of being scraped, next scraping the coating substance until the surface thereof remote from the bed approximates the other surface of the finished aerofoil, and finally removing the scraped coating substance from the bed in the form given it by the bed in conjunction with the scraping.
- 25 11. An apparatus for making aerofoils or the like comprising a bed, interchangeable templets, and a carriage for the templets movable across the bed.
- 30 12. An apparatus for making aerofoils or the like comprising a bed, interchangeable templets, a carriage for the templets movable across the bed, and means for adjusting the carriage to accurately position it relatively to the bed.
- 35 13. An apparatus for making model aerofoils comprising a bed, a scraper movable back and forth across the bed, and a carriage for the scraper adjustable toward and from the bed, to regulate the depth of the scrape.
- 40 14. An apparatus for making model aerofoils comprising a container for paraffin or the like, the paraffin within the container constituting a bed upon which the aerofoil is made, a scraper movable back and forth across the bed in scraping contact with the aerofoil, and a carriage for the scraper adjustable toward and from the bed to regulate the depth of the scrape.
- 45 15. An apparatus for making model aerofoils comprising a container for paraffin and the like, a templet having a scraping edge movable longitudinally of the apparatus to scrape the paraffin, and a carriage for the templet having associate adjusting means for regulating the depth of the scrape.
- 50 16. An apparatus for making model aerofoils comprising a container for paraffin or the like, a templet having a scraping edge movable back and forth across the paraffin in scraping contact therewith, the scraped surface of the paraffin constituting a bed upon which the aerofoil is made, a second templet having a scraping edge similarly movable, though in scraping contact with the aerofoil itself, a carriage for the templets, the templets being interchangeable and having a certain definite sequence as regards the order of their use, means for fastening the templets to the carriage, first one and then the other, and adjusting means associated with the carriage for regulating the depth of the scrape made by either or both the templets.
- 55 17. In an apparatus for making model aerofoils comprising a bed upon which the aerofoil is made, a scraper movable back and forth across the bed, a carriage for the scraper, means for guiding the carriage in moving it back and forth, and means for adjusting the carriage to accurately position the scraper relatively to the bed.
- 60 18. An apparatus for making model aerofoils comprising a frame, a bed upon which the aerofoil is made, a scraper movable back and forth across the bed, a carriage for the scraper, a guide for the carriage formed upon the frame at one side of the bed, and a carriage adjusting means, the guide for the carriage defining an axis about which it (the carriage) is adjusted.
- 65 19. An apparatus for making model aerofoils comprising a bed upon which the aerofoil is made, a scraper movable back and forth across the bed, a carriage for the scraper, means for adjusting the carriage toward and from the bed, and a guide for the carriage

carriage formed upon the frame at one side of the bed.

20. An apparatus for making model aerofoils comprising a frame, a bed upon which the aerofoil is made, means for centering the bed upon the frame, a scraper movable back and forth across the bed, a carriage for the scraper and a means for adjusting the scraper toward and from the bed to regulate

10 the depth of the scrape.

21. An apparatus for making model aerofoils comprising a frame, a bed upon which the aerofoil is made, a scraper movable back and forth across the bed, a carriage 15 for the scraper, means for guiding the carriage as it is moved back and forth, and means for adjusting the carriage toward and from the bed, the adjusting means being so related to the guide as to enter into and

20 form a part thereof.

22. An apparatus for making model aero-

foils comprising a frame, a bed upon which the aerofoil is made, means for centering the bed upon the frame, a scraper movable back and forth across the bed, a carriage for the 25 scraper, guide rails formed at opposite sides of the frame to direct the movement of the carriage in moving the scraper back and forth, an adjusting means mounted at one end of the carriage to regulate the depth of the scrape, the adjusting means comprising a thumb nut which bears upon the guide rail 30 of the frame.

23. An apparatus for making aerofoils and the like comprising a frame, a bed, adjusting means for centering the bed upon the frame, and cutting means movable across the bed to shape the aerofoil. 35

In testimony whereof I hereunto affix my signature.

JOSEPH G. COFFIN.
